UNITED STATES PATENT OFFICE.

HERMANN J. MÜLLER, OF NEW YORK, N. Y.

DESIGN FOR A CLOCK-STAND.

SPECIFICATION forming part of Design No. 16,714, dated June 1, 1886.
Application filed April 22, 1886. Serial No. 199,857. Term of patent 14 years.

To all whom it may concern:

Be it known that I, HERMANN J. MÜLLER, of the city, county, and State of New York, have invented a new and original Design for 5 Clock-Stands, of which the following is a full, clear, and exact description, reference being had to the accompanying drawing, making part of this specification, which represents a front elevation of the design.

10 The design relates to clock-stands; and it consists of a support, a representation of a flower with radial leaves in relief, the flower carrying a clock-dial at the center, and a bow at the lower end of the stem of the flower.

15 A in the drawing represents a support or stand; B, a flower having radial leaves b and a stem, B' , leaves B^2 branching out from the stem, the flower, stem, and leaves being arranged in

relief. At the center of said flower B a clock-dial, C, is arranged. A bow, D, is placed at 20 the lower end of the stem B' .

Having thus described my design, I claim as new and desire to secure by Letters Patent—

The design for a clock-stand, consisting of 25 a support, A, a flower, B, having radiating leaves b , a stem, B' , a clock-dial, C, at the center of the flower, and a bow, D, at the lower end of the stem B' , as shown and described.

In testimony that I claim the foregoing as my invention I have signed it this 21st day 30 of April, 1886.

HERMANN J. MÜLLER.
